UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

MECHANICAL MOVEMENT.

1,234,771.

Specification of Letters Patent. Patented July 31, 1917.

Application filed November 16, 1915. Serial No. 61,831.

To all whom it may concern:

Be it known that I, JOHN KIEWICZ, a citizen of the United States, residing at Boston, county of Suffolk, State of Massachusetts, have invented an Improvement in Mechanical Movements, of which the following description, in connection with the accompanying drawing, is a specification, like characters on the drawing representing like parts.

This invention relates to mechanical movements and particularly to a mechanical movement designed to convert a uniform rotary motion into an intermittent or variable rotary motion. A mechanical movement operating in this way is capable of a wide variety of uses, among which may be mentioned as an illustration, the operation of a feed cam for a sewing machine.

In many types of sewing machines the work is fed by means of a rotary feed cam, and it is desirable that the feed should be intermittent so that the feeding movement will occur when the needle is withdrawn from the goods and the work will be at rest when the needle is penetrating the goods.

My invention is adapted for use not only in giving intermittent rotary movement to the feed cam of a sewing machine, but is also capable of use in various other devices where an intermittent or variable rotary motion is desired. Hence the above reference to the sewing machine is merely for the purposes of illustration and not for the purpose of limiting the use to which the invention may be put.

One familiar way of converting a continuous rotary motion of a driving element into an intermittent rotary motion of a driven element is by means of a pawl-and-ratchet mechanism which derives its operation from the continuously-rotating driving element. While a pawl-and-ratchet mechanism may work satisfactorily where the machine is operating at a comparatively low speed, yet where the demands of use require high speed operation a pawl-and-ratchet is not always satisfactory because sometimes when the driven element is stepped forward by the operation of the ratchet, the momentum of the element will carry it beyond the desired point, thus giving it a longer step than was intended.

It is one of the objects of my present invention to provide a novel mechanism for converting continuous rotary movement into

intermittent or variable rotary movement which is positive in its action and which insures the correct stepping forward of the driven element at each operation even when the device is being operated under high speed conditions. I secure this end by connecting the driving and driven elements with gearing which is positive in its action, and by providing means whereby the rotative effect of the gear is partially or entirely nullified during one period of the cycle of operations and is then augmented during another period of the cycle of operations with the result that the driven element will be given the intermittent or variable motion in a positive manner and without any back-lash or loose play, such as is liable to be found in a device where a pawl-and-ratchet is used for this purpose.

In order to give an understanding of my invention, I have illustrated in the drawings a simple embodiment thereof which is sufficient to give an understanding of the principle, but I wish it understood that the device shown in the drawings is illustrative only and that the invention is not limited to the construction shown.

Figure 1 of the drawings is a plan view showing a mechanical movement embodying my invention;

Fig. 2 is a section on the line 2—2, Fig. 1. I have shown at 1 the driven element of the device which is in the form of a rotary member pivotally mounted to rotate about a stud or shaft 2. This driven element 1 receives its motion from a shaft 3 through suitable gearing which in the present embodiment of the invention comprises a worm 4 on the shaft 3 meshing with worm-teeth 5 formed on the driven element 1.

If the worm 4 were fast on the shaft 3 then, of course, the element 1 would rotate uniformly with the shaft 3.

My invention includes means whereby during a certain part of the revolution of the shaft 3 the rotative effect of the worm 4 on the element 1 is partially or entirely nullified, while during the next succeeding part of said revolution of the shaft 3 the rotative effect of the worm 4 on the part 1 is augmented. This successive nullification and augmentation of the rotative effect of the worm 4 on the shaft will result in giving to the element 1 either an intermittent rotary or a variable rotary movement, depending on the particular construction employed.

2

secure this alternate nullification and augmentation of the rotative effect of the worm 4 on the element 1 by mounting the worm 4 on the shaft 3 so that it can move longitudinally thereon but must rotate therewith. 5 If, for instance, the worm 4 is being moved longitudinally toward the right, Fig. 1, on the shaft 3, at the same time that the shaft is turning in the direction of the arrow *a*, 10 Fig. 1, the resultant motion which is given to the element 1 is the combined effect of the rotation of the worm 4 and its longitudinal movement, both of which tend to turn the element 1 in the direction of the arrow *b*. 15 On the other hand, if the worm 4 is being moved toward the left, Fig. 1, while the shaft 3 rotates in the direction of the arrow *a*, this movement to the left will nullify or 20 partially nullify the motion given to the element 1 by the rotation of the worm 4. If the extent of the longitudinal movement of the worm 4 toward the left Fig. 1 during the 25 time that the shaft 3 rotates through a predetermined angle has the proper relation to the speed of rotation of the shaft, such longitudinal movement will completely nullify the action of the worm 4 in rotating the element 1, and as a result said element will merely remain stationary. Therefore, by 30 giving the worm 4 a vibratory movement longitudinally of the shaft 3 while the latter is rotating, it is possible to vary the rotation of the driven element 1 so as to give it an intermittent rotative movement. If the shaft 35 3 is rotating uniformly, the particular character of the oscillating motion which the element 1 has will depend upon the relation between the vibratory movement of the worm 4 and the rotation of the shaft 3, and 40 it would be possible to make this relation such that the driven element 1 will be given a quick step forward, then a slow step forward, then a quick step forward, and a slow step forward, etc., or to give the element 1 a step 45 forward, a short step backward, a second step forward, a third step backward, etc., as well as to give it the intermittent motion.

The worm 4 may be mounted on the shaft 3 in any suitable way which will permit of 50 its being moved longitudinally of the shaft. In the construction herein shown the worm is provided with a hub 6 having one or more slots therein, said slots receiving rolls 8 carried by a pin or stud 9 extending from the shaft 3. This permits the worm 4 to have the movement longitudinally of the shaft while at the same time compelling the worm to rotate uniformly with the shaft. Any 55 other connection between the worm and the shaft which will permit of this operation 60 may be employed, however, without departing from my invention.

The shaft 3 is shown as mounted in bearings 10, but may be sustained in any suitable way. Said shaft may also be given its

rotary movement by any desired means. In the construction shown, said shaft 3 is driven from a shaft 11 by means of bevel gears 12, 13 and the shaft 11 is shown as having a pulley 14 thereon by which it is 70 operated from some suitable source of power. This particular arrangement, however, may be varied without departing from the invention, as the particular driving mechanism for the shaft 3 will depend 75 largely upon the machine or other elements with which this mechanical movement is being used.

Any suitable means may also be employed for giving the worm 4 its movement longitudinally of the shaft 3. I will preferably, however, use a cam or eccentric which is mounted either on the shaft 3 or is operating in time relation with said shaft 3. In the construction herein illustrated I employ 80 a cam 15 on the shaft 11 which is provided with a cam groove 16 in which operates a roll or pin on the end of an elbow-lever 17 pivotally mounted at 18. The other arm 19 of said elbow-lever has a roll or projection 23 operating in a groove 24 formed in a hub portion 22 of the worm 4. The cam groove 16 is so constructed as to give the elbow-lever 17 an oscillating movement about its pivot as the shaft 11 rotates, and 95 this oscillating movement results in vibrating the worm 4 back and forth on the shaft 3. The particular relation between the vibratory movement of the worm 4 and the rotation of the shaft 3 will, of course, depend upon the character of the cam 16, and 100 this will be varied to suit the requirements of use. If it is desired to give the driven element 1 an intermittent motion, then the cam groove 16 will be so designed that when 105 the roll is passing from the portion 20 of the cam groove to the position shown in Fig. 1, the worm 4 will be moved to the left at such a speed as to counteract the rotative effect of the worm on the element 1, and the 110 effect will be that of the worm 4 being screwed to the left by the worm gear. When the roll on the elbow-lever 17 is moving from the position shown in Fig. 1 to the portion 21 of the cam, the worm will be given a 115 movement toward the right Fig. 1. This movement of itself will turn the driven element 1 forwardly, but as the worm 4 is rotating while it is being moved longitudinally of the shaft, the oscillating motion given to 120 the element 1 is the combined effect of the rotation of the worm 4 and its movement longitudinally of the shaft. It will be understood, of course, that if the cam groove 16 is made to give the lever 17 a greater 125 throw than that herein shown, the result will be that when the cam-operated end of the lever 17 is moving downwardly, the element 1 will be given a forward movement, while when said end of the lever 17 is mov- 130

ing upwardly, the element 1 will be given a slight backward movement, while if the groove 16 is constructed to give the lever a less throw, the element 1 will have a fast forward movement while the cam-operated end of the lever 17 is moving downwardly, and a slow forward movement while said end of the lever 17 is moving upwardly.

It will be noted that the driving connection between the driving element and the driven element is a positive connection by which the driven element is at all times held under control and yet said connection is such that the desired intermittent or variable movement may be given to the driven element. The positive gearing connection between the driving and driven elements insures that all of the forward steps of the driven element will be of uniform extent even when the device is operated under high speed conditions, and thus entire accuracy in the operation of the driven element is provided for.

In the above description and in the claims I have referred to the effect on the driven element 1 of the bodily movement of the worm 4 to the left, Fig. 1, as nullifying, partially nullifying and retarding the rotative movement of said driven element due to the rotation of the worm 4, and the movement of the worm 4 to the right as augmenting such movement. By the term "retard" as thus used, I intend to include any action which partially or completely counteracts the rotative effect of the worm 4 on the driven element 1, and this may be such as to only slow down the element 1, or may be such as to hold said element stationary, or

may even be such as to move the element 1 backwardly slightly. The particular character of the variable motion which is given to the element 1 is also determined to a greater or less extent by the relation between the speed of rotation of the shaft 3 and the movement of the worm 4.

While I have illustrated a selected embodiment of my invention, I do not wish to be limited to the constructional features shown.

I claim:

1. In a mechanical movement, the combination with a rotatable shaft, of a worm mounted thereon for rotative movement therewith, but capable of movement longitudinally thereof, a driven element with which said worm meshes, means to rotate the shaft, and means actuated by the rotating means for the shaft to vibrate said worm longitudinally of the shaft as the latter rotates and in timed relation with the rotation thereof.

2. In a mechanical movement, the combination with a rotatable shaft, of a worm mounted thereon for rotative movement therewith but capable of movement longitudinally thereof, a driven element with which said worm meshes, a second shaft geared to the first-named shaft and by which said first-named shaft is rotated, and means actuated by said second shaft to vibrate the worm longitudinally of the first-named shaft as the latter rotates.

In testimony whereof, I have signed my name to this specification.

JOHN KIEWICZ.
